(57) **CLAIM**

The ornamental design for a television receiver, as shown and described.

DESCRIPTION

FIG. 1 is a front perspective view of a television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 3;

FIG. 11 is an enlarged view of the encircled portion 11 in FIG. 4;

FIG. 12 is an enlarged view of the encircled portion 12 in FIG. 5;

FIG. 13 is an enlarged view of the encircled portion 13 in FIG. 6;

FIG. 14 is an enlarged view of the encircled portion 14 in FIG. 7;

FIG. 15 is an enlarged view of the encircled portion 15 in FIG. 8;

FIG. 16 is an enlarged view of the encircled portion 16 in FIG. 8;

FIG. 17 is an enlarged view of the encircled portion 17 in FIG. 8;

(Continued)

FIG. 18 is an enlarged view of the encircled portion 18 in FIG. 8;

FIG. 19 is an enlarged view of the encircled portion 19 in FIG. 8; and,

FIG. 20 is an enlarged view of the encircled portion 20 in FIG. 8.

The broken lines in the figures depict portions of the television receiver which form no part of the claimed design. The dot-dash broken line circles depict the limits of the enlarged view and form no part of the claimed design.

1 Claim, 20 Drawing Sheets
